HARRY R. CANFIELD, OF NEW YORK, N. Y., ASSIGNOR, BY MESNE ASSIGNMENTS, TO
FREDA SOSS, OF NEW YORK, N. Y.

INVISIBLE HINGE.

941,672.

Specification of Letters Patent. Patented Nov. 30, 1909.

Application filed March 31, 1909. Serial No. 487,009.

To all whom it may concern:

Be it known that I, HARRY R. CANFIELD, a citizen of the United States, and residing at New York, in the county of New York and State of New York, have invented certain new and useful Improvements in Invisible Hinges, of which the following is a specification, such as will enable those skilled in the art to which it appertains to make and use the same.

This invention relates to what are known as invisible hinges; and the object thereof is to provide an improved device of this class designed for use in connection with doors, gates, sashes or the like, and also piano and organ constructions and in cabinet work of various kinds and classes; and with this and other objects in view the invention consists in a hinge of the class specified constructed as hereinafter described and claimed.

The invention is fully disclosed in the following specification, of which the accompanying drawing forms a part, in which the separate parts of my improvement are designated by suitable reference characters in each of the views, and in which:

Figure 1 is a side view of a hinge made according to my invention and looking in the direction of the arrow *x* of Fig. 3, Fig. 2 a section of the hinge on the line 2—2 of Fig. 1 and showing the hinge applied to a door frame and door, and showing the door in a closed position, Fig. 3 a view similar to Fig. 2 but showing the door open, Fig. 4 a view similar to Fig. 1 but showing only part of the hinge and showing a modification, Fig. 5 a partial transverse section on the line 5—5 of Fig. 4, Fig. 6 a section on the line 6—6 of Fig. 1 but showing a modification and showing the hinge applied to a door and door frame, and showing the door in a closed position, and;—Fig. 7 a view similar to Fig. 6 but showing the door open.

In the drawing forming part of this specification, I have shown at *f* a part of a door frame and at *d* a part of a door, and in the practice of my invention I provide a hinge comprising two similar main plates or leaves *a* and *b* which are preferably formed by folding a sheet of steel or other metal longitudinally, and these plates or leaves are

provided with knuckles *a*² and *b*² respectively.

I also provide two supplemental hinge plates *c* and *d*, and these hinge plates *c* and *d* are provided at their opposite edges with knuckles *c*² and *d*² respectively as clearly shown in Fig. 1, and the supplemental hinge plate *c* is provided with a transversely ranging arm *c*³, and the supplemental hinge plate *d* with a transversely ranging arm *d*³, and the main hinge plates or leaves *a* and *b* are provided with transversely ranging recesses *a*³ and *b*³ adapted to receive the arms *d*³ and *c*³ of the supplemental hinge plates *c* and *d*. The supplemental hinge plates *c* and *d* are connected by a pintle pin *e* passed through the knuckles *c*² and *d*² at one edge thereof, and the said supplemental hinge plates *c* and *d* are connected respectively with the main hinge plates or leaves *a* and *b* by pintle pins *f*³ and *g* as shown in Fig. 1, one of said pintle pins being passed through the knuckles of the plate or leaf *a* and the corresponding knuckles of the supplemental hinge plate *c*, and the other being passed through the knuckles *b*² of the main hinge plate or leaf *b* and the corresponding knuckles *d*² of the supplemental hinge plate *d*.

When the parts of the hinge are connected in the manner described and as shown in Fig. 1, the arms *c*³ and *d*³ of the supplemental hinge plates *c* and *d* enter and will swing in the transverse recesses *b*³ and *a*³ in the inner or adjacent side edges of the plates or leaves *a* and *b*, and said arms *c*³ and *d*³ are slotted longitudinally as shown at *c*⁴ and *d*⁴ in Figs. 2 and 3, and passed through the lower end portion of the main hinge plate or leaf *a* and the upper end portion of the main hinge plate or leaf *b* are pins *h* and *i* which pass through the slots *d*⁴ and *c*⁴ in the arms *d* and *c*.

In practice the main hinge plates *a* and *b* are secured in the frame *f* of the door *d*⁵ and in the door *d*⁵ as shown in Figs. 2 and 3, and said plates or leaves are counter sunk in the frame and door as clearly shown in said figures, and the said frame and door are also provided respectively with recesses or chambers *f*² and *d*⁶ adapted to receive the

arms d^3 and c^3 of the supplemental hinge plates c and d in the operation of the door on its hinge or hinges and as shown in Fig. 2.

With this form of construction, when the door d^5 is closed the hinge is entirely concealed in the abutting faces of the door frame and door as clearly shown in Fig. 2, and the said door may be swung through an arc of one hundred and eighty degrees as shown in Fig. 3, and in the movement of opening the door it is swung clear of the door frame so as to avoid any moldings or ornamental work with which said door frame may be provided, this operation being clearly indicated in Fig. 3.

With this construction the door must be opened and closed by hand, but in Figs. 4 and 5 I have shown means whereby the door may be automatically closed and held in the closed position. In order to accomplish this result I provide a spring j which is wound on the central pin or pintle e , and which is provided with two arms j^2 and j^3 which are wound around or partially around the pintle pins f^3 and g , and this spring is preferably placed centrally of the hinge, but may be placed in any desired position and a number of said springs may be provided if desired, and in order to accommodate the same the knuckles of the plates or leaves a and b and of the supplemental hinge plates c and d are shortened.

In Figs. 6 and 7 I have shown a modification of this spring construction, in which I place either in the door frame or door, in the door frame as shown in the drawing, and in the recess or chamber f^2 therein a spiral spring k , and the arm d^3 of the supplemental hinge plate d is connected by means of a link k^2 with a disk or plate k^3 on which one end of said spring bears, the other end thereof bearing on the main hinge plate or leaf a , and the spring k will operate as will be readily understood to close the door d^5 and hold it in a closed position.

It will be understood, of course, that if the spring k is used in the door instead of being used in the door frame, the said spring will be placed in the chamber or recess d^5 and will be connected with the arm c^3 of the supplemental hinge plate c , and said spring device may be used both in the door d^5 and door frame f if desired.

It will be observed that the knuckles a^2 and b^2 on the plates or leaves a and b are offset at one side of said plates or leaves so that the centers of said knuckles are not in the central planes of said plates or leaves, and it will also be observed that the arms c^3 and d^3 of the supplemental hinge plates c and d are wider where the pintle or pin e passes therethrough than at the opposite ends, and the longitudinal slots c^4 and d^4 in said arms

are curved inwardly of the pivotal support or connection formed by the said pintle e , 65 and this construction enables the separate parts of the hinge to fold together as shown in Fig. 2 and also facilitates the movement of said parts in the beginning of the operation of opening the door.

It will be understood that my improved hinge may be made of any desired strength, and the arms c^3 and d^3 of the supplemental hinge plates c and d may also be made of much greater relative dimensions or strength 75 than herein shown and described if found necessary.

Having fully described my invention, what I claim as new and desire to secure by Letters Patent, is:—

1. A hinge composed of two main plates or leaves and supplemental plates hinged thereto and to each other, said supplemental plates being provided with arms which enter transverse recesses in the main hinge plates 85 or leaves and which are provided with longitudinal slots, and said main hinge plates or leaves being provided with stationary pins which pass through said slots.

2. A hinge composed of two main plates 90 or leaves provided at one edge with knuckles, supplemental plates provided at one edge with knuckles, said main plates or leaves and said supplemental plates being connected by pintles passing through said 95 knuckles, and said supplemental plates being also provided at their opposite edges with knuckles and being connected by a pintle passing therethrough, said main plates or leaves being provided with transverse recesses, and said supplemental plates with arms movable in said recesses and provided with longitudinal slots, and said main plates or leaves being provided with stationary pins which pass through said slots.

3. A hinge composed of two main plates or leaves and supplemental plates hinged thereto and to each other, said supplemental plates being provided with arms which enter transverse recesses in the main hinge plates 110 or leaves and which are provided with longitudinal slots, said main hinge plates or leaves being provided with stationary pins which pass through said slots, and a spring device for holding the parts of the hinge in 115 a closed position.

4. A door provided with a hinge composed of two main plates or leaves and supplemental plates hinged thereto and to each other, said supplemental plates being provided with arms which enter transverse recesses in the main hinge plates or leaves and which are provided with longitudinal slots, and said main hinge plates or leaves being provided with stationary pins which pass 120 through said slots, said main plates or leaves

being secured in the door frame and door, and said door frame and door being provided with recesses adapted to receive the movable parts of the hinge, and a spring connected with the hinge for holding the door in a closed position.

In testimony that I claim the foregoing as

my invention I have signed my name in presence of the subscribing witnesses this 30th day of March, 1909.

HARRY R. CANFIELD.
